(57) **CLAIM**

The ornamental design for a display screen with graphical user interface, as shown and described.

DESCRIPTION

FIG. 1 is a front elevation view of a display screen with graphical user interface, showing our new design;

FIG. 2 is the second image thereof,

FIG. 3 is the third image thereof,

FIG. 4 is the fourth image thereof; and,

FIG. 5 is the fifth image thereof.

The appearance of the transitional image sequentially transitions between the images shown in FIGS. 1-5. The process or period in which one image transitions to another image forms no part of the claimed design.

The outmost dot-dashed lines in the figures show a display screen or portion thereof and form no part of the claimed design.

The broken line showing of text and graphic elements forms no part of the claimed design.
